United States Patent Office.

JOHN BRAENTIGAM AND HENRY BRAENTIGAM, OF CHICAGO, ILLINOIS.

Design No. 4,055, dated May 24, 1870.

DESIGN FOR A DOG-MUZZLE.

The Schedule referred to in these Letters Patent and making part of the same

To all whom it may concern:

Be it known that we, JOHN BRAENTIGAM and HENRY BRAENTIGAM, both of Chicago, in the county of Cook and State of Illinois, have invented a certain new and original Design for Dog-Muzzles, of which the following is a specification, reference being had to the accompanying drawing.

Our invention relates to designs for dog-muzzles, and consists in producing a design of a novel form or pattern for such articles.

The drawing represents a perspective view of our design, and shows the form, shape, and configuration of the whole, as well as of the several parts combining to make up the whole dog-muzzle.

Having thus described our invention,

What we claim is—

The form, shape, or configuration, substantially as shown and described, as a design for a dog-muzzle, as set forth.

JOHN BRAENTIGAM.
HENRY BRAENTIGAM.
